[57] ABSTRACT

A novel shoe store and shoe selection apparatus is dis-

closed. The store having a customer entrance, a central customer seating area, a shoe display located near the customer entrance, shoe display means in said shoe display area comprising support means to support at least one row of shoe display bags, an enclosed shoe inventory area remotely located from said customer entrance and shoe retrieval means in said shoe inventory area comprising an overhead conveyor for supporting shoe bags of substantially the same size and number as in said shoe display means.

The apparatus comprises a fixed display means having a plurality of shoe display bags with each bag having shoes of substantially the same size therein having only one shoe of a pair in the display bag and having the bags arranged in order of shoe size. The inventory is maintained in a shoe retrieval means having the shoe bags therein the sum of which contains an identical inventory of shoes to the shoe bags in the display means, with the retrieval bags grouped according to shoe size and attached to the overhead conveyor.

SHOE STORE AND SHOE SELECTION SYSTEM**BACKGROUND OF THE INVENTION**

A need exists in the retailing of shoes for a system of displaying shoes so that the customers may view the stock of the store and select styles and sizes for purchase without constant attention from sales personnel.

Furthermore, the increasing cost of floor space and sales personnel, along with other overhead expenses, necessitates the possession of a large inventory of shoes in a relatively small space. None of the present techniques of marketing shoes at retail level meet these needs.

In U.S. Pat. No. 3,669,276, there is disclosed a shoe bag for use in a system of marketing shoes in a retail establishment. The bag disclosed therein is an elongated bag with intermediate supports for a single shoe on each support. Also, it is disclosed therein that a system of marketing shoes is possible through use of such bags wherein each shoe of a pair is located in two different bags, one bag being located in a display area and another bag in an inventory area. This is done so that the customer may see the various styles of shoes available in each size but with only one shoe of a pair displayed so that shoplifting is minimized.

SUMMARY OF THE INVENTION

A new store and system for retailing shoes has been invented. The store comprises a customer entrance, a shoe display area located near said customer entrance with shoe display means in the display area. The shoe display means comprises support means to support at least one row of shoe display bags. An enclosed shoe inventory area is remotely located from said shoe store entrance and contains shoe retrieval means comprising an overhead conveyor for supporting shoe bags which are preferably of larger size than those in the display area although they may be of substantially the same size and number as are present in the shoe display means.

The invention also includes an automated shoe selection apparatus comprising a fixed display means having a plurality of shoe display bags and having only one shoe of a pair, preferably having said bags arranged in order of increasing shoe size. Shoe retrieval means cooperates with the fixed display means in that the second shoe of each pair in the shoe display resides in the retrieval means. The retrieval means comprises a sufficient number of shoe bags to store the same number of shoes which are present in the display means. The shoe bags in the display area preferably each have 10 to 12 pockets for receiving a single shoe while the shoe bags in the retrieval means each has preferably 12 to 16 pockets, and it is generally preferred that the shoe bags in the retrieval area have a greater number of pockets per bag so that fewer bags are required in the retrieval area and less space therefore required. In the display area and the retrieval area the shoe bags are grouped according to shoe size.

Shoe bags particularly useful in this invention and described and claimed in U.S. Pat. No. 3,669,276 by the inventor hereof, the disclosure of U.S. Pat. No. 3,669,276 being entirely incorporated herein by reference.

Shoe bags utilized in this invention should have an end opening rather than a side opening. Shoe bags disclosed in Blough, U.S. Pat. No. 3,184,293 and Berg,

U.S. Pat. No. 1,847,066 may be utilized in practicing the instant invention although such bags preferably would be modified to accommodate only one shoe on each shoe support and preferably be no wider than about one shoe width.

The instant invention is particularly advantageous inasmuch as an inventory of about 1200 to 1800 pairs of shoes can be displayed and stocked in a store area of only about 600 square feet while still providing customer seating facilities, sales office space and employee facilities. A typical stocking of inventory for a ladies shoe store is about 1200 to 1800 pairs of shoes in sizes of from about 4½ to about 10 in about three standard widths. It is further advantageous in that shoe size and style selection may be made by the customer with very little, if any, attention from sales personnel. Also, the limited space required and the means provided for retrieval of shoes is unique and very advantageous.

FIG. 1 is a plan view of a compact shoe store having a shoe display area and a shoe inventory retrieval area.

FIG. 2 is an elevational view of a shoe bag on a display support.

FIG. 3 is an elevational end view of the shoe bag illustrated in FIG. 2.

FIG. 4 is a perspective view of shoe bags supported on a retrieval conveyor.

FIG. 5 is a section view the conveyor and an attached bag shown in FIG. 4.

FIG. 6 is a perspective view of a shoe display rack.

FIG. 7 is an elevational view of a hanger for attaching shoe bags to a support.

DESCRIPTION OF PREFERRED EMBODIMENTS

In FIG. 1 a plan view of a novel retail shoe store and novel shoe selection apparatus is illustrated. An elongated shoe display area 10 is located near customer entrance 11. The customer entrance is typically located at the front of the store, which is generally much narrower than the store length. Store frontage is generally more expensive so it is preferred to have an elongated store with a modest front dimension, for example, from about 12 to about 20 feet in width. The shoe display area comprises an area of about 2 to about 3 feet in width and about 20 to about 40 feet in length with a typical commercial establishment being about 25 to 35 feet in length. In the shoe display area a support structure to support a row of shoe bags of the type illustrated in FIG. 6 is preferred.

The shoe display support may be of the type illustrated in FIG. 6 although other support devices may be utilized. It is preferred that the shoe bags be supported in single rows with the rear portions of the bag in substantial contact with an outer wall of the store and the open ends of the bags facing outward. The rows of bags may be arranged in order of increasing size of shoes contained therein. Also, the shoe bags are preferably color coded so that shoes of a particular size are all in bags of the same color. Also, shoes of a common size, for example, sizes 3 through 8 in ladies shoes may occupy bags in separate rows in order to provide maximum access without undue crowding of customers. A pair of rows of shoe bags 12 having open ends 13 facing towards the center of the store on either side of the store permits customers to substantially encircle the display. The shoe display area should accommodate from about 120 to about 180 shoe bags 12 each having space to accommodate about 10 to 12 shoes.

50 The shoe display support may be of the type illustrated in FIG. 6 although other support devices may be utilized. It is preferred that the shoe bags be supported in single rows with the rear portions of the bag in substantial contact with an outer wall of the store and the open ends of the bags facing outward. The rows of bags 55 may be arranged in order of increasing size of shoes contained therein. Also, the shoe bags are preferably color coded so that shoes of a particular size are all in bags of the same color. Also, shoes of a common size, for example, sizes 3 through 8 in ladies shoes may occupy bags in separate rows in order to provide maximum access without undue crowding of customers. A pair of rows of shoe bags 12 having open ends 13 facing towards the center of the store on either side of the store permits customers to substantially encircle the display. The shoe display area should accommodate from about 120 to about 180 shoe bags 12 each having space to accommodate about 10 to 12 shoes.

An elongated customer seating area 25 is preferably located near the center line of the store to provide seating accommodations for about eight to 16 customers. Also, a shoe retrieval area is preferably located along one sidewall, preferably the sidewall which contains the fewest shoe bags. It is preferred to have an unequal number of shoes bags along opposite walls in order to provide the maximum amount of space along one wall to locate said retrieval means. The shoe retrieval area preferably includes an area adjacent a portion of the backwall as well. In FIG. 1 an L-shaped conveyor 26 is illustrated. The conveyor 26 is powered by a remote motor wired so that a particular section of conveyor 26 can be selected and caused to be moved adjacent the stock retrieval opening 27. The stock conveyor 26 preferably contains the bags to provide storage for the same number of shoes which are present in the shoe display area 10. It is preferred that each bag in the shoe retrieval means have a shoe capacity at least as large as a single bag in the display area. In the display area, customer considerations such as aesthetics, convenience and the like dictate that each bag hold 10 to 12 shoes while the desirability of effectively utilizing storage space makes the use of longer bags having a shoe capacity of 12 to 16 shoes preferable. If bags of the same size are utilized, then each bag supported on the stock conveyor has a substantially identical mate in the shoe display area. The stock conveyor 26 may be selectively programmed so that a particular bag may be automatically positioned beside stock opening 27, for example, if shoe sizes 6AA are in a particular bag or in a particular group of bags, the pressing of an appropriate button on a control panel can move the bag or bags containing shoe sizes 6AA to a position along side the stock opening 27. The stock conveyor 26 is of conventional design and may be substantially similar to conveyors presently utilized in dry cleaning establishments. In fact, by utilizing a hanger of the type illustrated in FIG. 8, the bags may be similarly supported in both the shoe display area and on the stock conveyor.

The conveyor 26 may be manually operated and the appropriate bag selected by its color and associated index.

The conveyor with shoe bags attached occupies less space than other means of stocking or inventorying single shoes matching the shoes in the display area. Alternatively, a stock of shoes similar to the display stock can be formed by hanging two rows of bags with a narrow central aisle therebetween. However, inasmuch as it is desired to maintain the matching shoe to the shoe displayed in the shoe display means in an enclosed area, the space required is greater than that required for the above-described retrieval arrangement. Unless the shoe inventory or stock is maintained in an enclosed area it will be possible for customers to have access to that area and to place in their possession both shoes to a particular pair. Thus, the likelihood of shoplifting will be increased. A stockroom arrangement having fixed rows of bags requires an area the same length as the shoe display area with a width of at least about 6 feet so that personnel could pass between the double rows of bags to select the matching shoe. This would be more time consuming for the sales personnel and the stock room would require a greater area. A stock room using a conveyor system requires less than about 4½ feet of width and may require only about 3 feet and requires an overall area substantially less than

the shoe display area and associated aisles. Also, the sales clerk may be preparing the sales slip while waiting for the conveyor to bring the correct bag to the shoe retrieval station rather than manually searching the stock for the matching mate.

5 A shoe bag particularly useful in the instant invention for displaying and stocking shoes is illustrated in FIGS. 2 and 3. The bag 12 has an open end 13 and a closed end 14. The sides 15 and 16 are preferably formed of a single sheet of flexible material. A top loop 17 is formed of the fabric so that it can slide about a support rod or other slender elongated support. The loop 17 may be a continuous loop or it may be affixed with a snap means or zipper or other means of closing the loop so that it will support the weight of a filled bag. Bags of this type are more particularly described in U.S. Pat. No. 3,669,276.

10 A hanger particularly useful in this invention is illustrated in FIG. 7. This hanger may be used in supporting bags in the shoe display and for supporting bags on a retrieval conveyor.

15 One of the problems involved in self-service sale of shoes is maintaining the display of shoes. Since the customers will frequently be removing shoes from the shoe display means, trying them on and returning the shoes to the shoe display, it will frequently occur that the shoes will be replaced in the wrong shoe bag or in the wrong slot in a particular shoe bag. Thus, a readily observable indexing means is desirable so that the sales personnel may quickly scan the shoe display and determine if any shoes have been placed in the wrong slot. One particular advantageous index means comprises color coding of the bags in conjunction with a numbering system.

20 As indicated hereinabove, it is preferred to place shoes of the same size in bags of the same color. Thus, the placing of all size 6 shoes in, for example, blue bags renders it easy to determine when the stock of size 6 shoes is getting low and with the appropriate color code it is easily determined when a shoe has been placed in the wrong bag. A colored tag or decal of the same color as the bag is attached to a shoe which is to be deposited in a bag of that color. The placement of a shoe of one size in a bag of shoes of another size is quickly detected by the color tag contrasting with the color of the bag.

25 It is very important in a self-service retail establishment to have the stock appropriately placed so that the customer will be able to find exactly what he or she desires without undue searching. Thus, the affixing of a code or index means to the shoes to match the bag in which it is placed enhances the use of the shoe display.

30 In FIG. 4 a conveyor system for retrieval of stocked shoes is illustrated which comprises an overhead rail 20 to which rollers 18 glide and have pendent therefrom an elongated link 19 which interlocks with links on either side to provide means for supporting bags attached by hangers. The elongated link 19 has a plurality of openings in which the hook of a hanger such as that illustrated in FIG. 7 can be inserted. The color coding of bags in the shoe retrieval apparatus greatly facilitates the retrieving of the stock, especially when the conveyor is not automated to stop at a preselected position. An operator can initiate movement of the conveyor and then readily stop the conveyor when the appropriate bag appears at the stock removal opening. For example, a sales clerk having a shoe with a blue tag thereon operates the conveyor until the blue bags ap-

pear. The conveyor is then stopped and the appropriate or matching shoe is located in one of the blue bags.

The conveyor illustrated in FIG. 4 has an overall L-shape adapted to fit into a compact shoe store as illustrated in FIG. 1 wherein the longer length "L" extends along the longer dimension of the store while the shorter length "l" extends along the shorter dimension of the store. Although a linear shaped conveyor is readily usable in this invention, it is preferred to utilize an L-shaped conveyor to the maximum advantage of 10 available space.

A pair of idler wheels 21 and 22 placed angularly opposite one another and in contact with elongated links 19 of the conveyor form the corners of the conveyor. A third idler wheel 23 is located at one end of the conveyor. The idler wheels make contact with links 19 to guide the links around the turns of the conveyor. Although idler wheels could be eliminated, they do prevent excessive swinging of the load at the corners and further assist rollers 18 to maintain contact with rails 20. A drive wheel 24 engages links 19 to propel the chain of interlocking links around the conveyor. Drive wheel 24 is preferably located near the end of short length l. The drive motor, associated gear reduction mechanism and the like are also preferably located 25 near the end of short length l.

Rail 20 is an elongated continuous support rail having an overall L-shape and forming a support for rollers 18. As illustrated in FIG. 5, rail 20 is preferably a channel-like member.

An end view of the conveyor with shoe bag attached is illustrated in FIG. 5. FIG. 6 illustrates a shoe bag attached to a support apparatus forming a shoe display means.

Although the invention has been described herein by reference to specific embodiments, it is not intended to be limited solely thereto, but to include all the variations and modifications falling within the scope of the appended claims.

I claim:

1. A novel compact shoe store comprising:
- a. a store entrance;
- b. a shoe display area located proximate said store entrance;
- c. shoe display means in said shoe display area comprising support means to support at least one row of shoe display bags;
- d. an enclosed shoe inventory area remotely located from said store entrance;
- e. shoe retrieval means in said shoe inventory area comprising an overhead conveyor for supporting shoe bags of substantially the same size and number as said shoe display means.

2. An automated shoe selection apparatus comprising:

- a. fixed display means having a plurality of shoe display bags thereon, each bag having single shoe holding means,
- b. shoe retrieval means comprising conveyor means having attached thereto the same number and type of shoe bags as the display means, said retrieval means having shoe bags of the same color as shoe bags in said display means wherein each shoe bag of the same color contains shoes of substantially the same size,
- c. propulsion means to move said bags along said conveyor.
